UNITED STATES PATENT OFFICE.

CHARLES TRUESDALE, OF CINCINNATI, OHIO.

IMPROVEMENT IN FIRE-BACK LININGS.

Specification forming part of Letters Patent No. 147,881, dated February 24, 1874; application filed January 26, 1874.

To all whom it may concern:

Be it known that I, CHARLES TRUESDALE, of Cincinnati, Hamilton county, Ohio, have invented a new and useful Lining or Fire-Back for Stoves, of which the following is a specification:

My said improved fire-back or lining consists, essentially, of a congeries of separable plates, blocks, or sections, capable of being attached to or detached from a suitable frame or backing, the said blocks, in their attached condition, being insulated from one another sufficiently to avoid the liability of the jamming or warping incident to the excessive expansion of cast-iron when repeatedly heated, so as to seriously distort or contract the fire-chamber. The distinct, isolated, and separable character of my component lining-blocks renders each one free from any influence that might otherwise arise from distortion of the contiguous portions; and their detachability enables the easy removal of a damaged, and the insertion of an undamaged, block, without the necessity of taking out and replacing an entire fire-back or lining. The said lining and the inclosing parts of the stove are, preferably, so formed as to secure a free admission of fresh air to every part of the lining.

I will describe my improvement as adapted for use as the fire-back of a common cook-stove, for which purpose it is more especially designed.

In the accompanying drawings, Figure 1 is a perspective view of my improved sectional fire-back detached from the stove, and resting upon the grate-bearer. Fig. 2 is a section of the fire-back at the line X X. Fig. 3 is a vertical section at the line Y Y, showing my improved fire-back in position within a cook-stove. Fig. 4 is a perspective view of the lining-frame in position on the grate-bearer. Fig. 5 is a perspective view of the rear side of one of the said blocks. Figs. 6, 7, and 8 show modifications of my block-fastenings, the latter illustration being drawn on an enlarged scale.

A may represent any suitable grate frame or bearer, the form here shown being adapted for a tipping or dumping grate, such as employed by me. From the rear edge of the bearer A projects a flange, B, widened at intervals to form lugs C, upon which rests the

lower edge of my lining-frame or backing D, which may be of form substantially as represented—that is to say, concave in vertical section on its front side—and having the oblique slots E E' in diverging pairs, as shown, those portions F of the backing between the slots of each respective pair being concave in horizontal section, for the two-fold purpose of insuring strength and elasticity to the backing, and of affording an air space or chamber for the cooling of the section, as hereinafter explained.

For the more effectual admission of air, as aforesaid, and to lighten the casting, each portion F may have an orifice, f.

My sectional fire-plates or blocks G are curved in vertical section to correspond with the said backing, and have projecting rearwardly from their top edge a flange, H, which, *in situ*, rests upon the top flange d of the backing D. Projecting from the lower end of each section is a hook, I, which, *in situ*, engages underneath the flange B of the grate-bearer. The front or fire face of each section is, preferably, ribbed, J, for the several purposes of stiffening the same, and of holding ashes, whose non-conducting properties protect the section from intense heat, and also serve the purpose of upholding the fuel and admitting air to its rear portion. Projecting from the rear of each section are hooks K K', which, being inserted through the slots E E', engage behind the flaring portions or bars F of the backing D, and, being slid down to their places, tightly embrace said portions. The backing, thus lined with fire-blocks, is inserted in the stove, and the hooks I engage under the flange B of the bearer A. The blocks G are of such width as, when in place, to leave intervals between them sufficient to avoid any injurious contact under any possible swelling of the blocks by heat, and these intervals may be incidentally useful in affording passages for air.

I have selected, to illustrate my invention, a form successfully used in my manufacture, but reserve the right to vary the same in non-essential particulars; for example, the hooked fastenings K K' may be replaced by a single hook, Fig. 6, engaging in a suitable slot in the backing; or by a headed pin, or a screw-threaded pin and nut, as in Figs. 7 and 8, respectively;

and the ribs J and air-passage F *f* may be omitted.

Whichever form of retaining device is employed for coupling the removable blocks to the frame, it is preferred to have said device attached at or near the middle of such block. When thus applied, it is evident the blocks will be free to expand and contract in every direction without exerting any injurious strain upon the hooks, lugs, pins, or bolts, which advantage would not be obtained in case the retaining devices were situated near the sides or ends of the blocks, or if the latter were inserted in a frame, and so surrounded with metal as to necessitate the cracking either of the blocks or frame itself.

It will be seen that any expansion of a block will rather loosen than tighten the grasp of the hooks K K' upon the part F; and, consequently, that there can be no danger of warping or straining the block, or that to which it is attached. The hook-shaped lugs at the bottom of the blocks constitute another advantageous feature peculiar to the fire-back, because, by engaging

under the grate-frame, they effectually prevent the blocks being elevated and dislodged from their proper position in shipping, or by prying action of the poker when the fire is stirred by a careless operator.

I claim herein as new and of my invention—

1. The backing D, constructed with flaring and scalloped ribs F and flanges d, substantially as and for the purposes described.

2. The separable fire-plates G, constructed with flanges H and hooks I, in combination with the backing D, substantially as and for the purposes set forth.

3. The backing-frame D E E' F, having the air-ducts *f*, in combination with the hooked blocks G and grate-bearer A B C.

In testimony of which invention I hereunto set my hand.

CHARLES TRUESDALE.
